UNITED STATES PATENT OFFICE.

WILLIAM H. WELSH, OF COLLINGSWOOD, NEW JERSEY, ASSIGNOR OF ONE-THIRD TO CHARLTON H. ROYAL AND ONE-THIRD TO JAMES F. GOUNLEY, OF PHILADELPHIA, PENNSYLVANIA.

PROCESS OF PRODUCING MATRICES.

No. 874,353.

Specification of Letters Patent.

Patented Dec. 17, 1907.

Application filed April 28, 1907. Serial No. 369,789.

To all whom it may concern:

Be it known that I, WILLIAM H. WELSH, a citizen of the United States, and a resident of Collingswood, Camden county, New Jersey, have invented a Process of Producing Matrices, of which the following is a specification.

My invention relates to the production of matrices and the subsequent electrotypes made therefrom for use in the reproduction of typed and half-tone matter for books, magazines, and other matter of a similar nature, by the art of printing, and it consists of an improved process of producing such matrices.

My improvements may be best described by reference to the accompanying drawings, in which:

Figure 1, represents a sectional elevation 20 of a combined type and half-tone form illustrating the first step in the process forming the subject of my invention; Fig. 2, is a similar sectional view showing the next step in the process; Figs. 3 and 4, are similar sectional 25 views showing further steps in the process; Fig. 5, is a sectional view illustrating the impression taken from such combined type and half-tone form, which impression is to be subsequently treated in the usual method 30 of making an electrotype, and Fig. 6, is an enlarged view of a portion of Fig. 5, showing the electroplated deposit or shell thereon.

The ordinary method of making electro- 35 types from type matter, is to make a wax impression, black-lead the same, oxidize such black-lead, place the oxidized impres- 40 sion in the electroplating bath, and when a sufficient deposit is made thereon, strip such shell from the wax impression, and back and finish the same in the usual manner.

In the making of magazine pages, nearly 45 all of them have half-tone insets, and it has been impossible to secure a satisfactory wax matrix of the combined type and half-tone form. This is due to a number of causes, among which may be mentioned the fact 50 that the type face stands much higher from its body than the lines of the half-tone, and consequently when the latter is in the center 55 of a sheet there is more wax for the half-tone to displace than adjacent the types and consequently there is danger of the half-tone slipping over the wax surface, and of the wax spreading over the types immediately sur-

rounding the half-tone. Further, in coating 55 the wax impression of the half-tone, the fine lines of the same become filled with black-lead and it is practically impossible to secure a satisfactory electroplate therefrom. In all instances, the wax impressions for half-tones 60 are more or less imperfect, and when a very thin-lined light-impression half-tone is em- 65 ployed, it is almost impossible to secure a perfect electrotype from a wax impression of the same, consequently it is now proposed to 70 make metal impressions from the half-tones and then these metal impressions are sepa- 75 rately electroplated and the finished electro- type from the half-tone is built in or other- 80 wise combined with the electroplate of the type matter. This practice is more or less satisfactory for flat platen printing presses, but in all printing presses employing curved platens around which the printing plates are 85 secured, there is always danger of the inserted half-tone block breaking loose from its fastenings and thereby spoiling the work, and in some instances partially wrecking the parts.

I propose to overcome all of these difficulties by producing a combined metal and wax matrix from the combined type and half- 90 tone page form, from which combined metal and wax matrix I can make a single, perfect electrotype in which the half-tone portion, 95 being impressed in the metal, will come forth with all its lines clean and sharply defined. I can accomplish this result in two ways, 100 which are as follows: The type-set page form, indicated at 1, which is to receive the half-tone inset 2, is, of course, prepared with a re-cess or space 3 for the reception of such half-tone which is preferably removed from its block. The half-tone prepared in the usual manner by photographing the original upon a metal plate which is afterwards etched to 105 permit reproduction of the picture, is placed in this space in the typed page, and a sheet 4 of relatively thin metal, approximately from 1/32 to 3/64 inch in thickness, is placed over the half-tone; such metal plate exactly fitting the space left in the typed page in which the half-tone is mounted. A layer 5 of relatively soft or yielding material, paper for instance, is placed on top of this metal plate, and then the latter is subjected to pressure. No specific pressure is employed except that it should be sufficient to cause the necessary

displacement of the metal of the plate, to form in the same the lines of the half-tone. The form with the half-tone and impressed-metal-plate is then withdrawn from the press and 5 the usual wax plate 6 put over the whole of the same, and then returned to the press and subjected to pressure which forces the wax against the type as in the ordinary manner, such wax at the same time picking up the 10 metal half-tone-impressed plate which remains embedded in the wax matrix, and then the whole is black-leaded in the usual manner and placed in the electroplating bath. The 15 black-leading, however, need not extend to the metal plate. The other method is to form the metal plate impression from the half-tone, wholly independent of the type and the formation of the wax matrix; the 20 page form being built up so as to provide a recess in the wax for the reception of the half-tone; then to insert the metal impression in the recess of the wax matrix, and then to electroplate the combined matrix in the usual manner. The latter method, however, is 25 not as satisfactory as the former, as there is the necessity of carefully adjusting the metal half-tone-impressed plate with respect to the wax matrix so that the finished electrotype will have the same level or face.

30 I speak of a metal plate, and there are numerous metals which may be used to receive the impression from the half-tone. In practice I have employed lead plates of approximately the thickness noted, and thin sheets 35 of foil.

I claim:

1. The process of forming matrices for the production of electrotypes from combined half-tone and type forms, which consists in 40 making a metal impression of the half-tone, assembling the type and half-tone impression in proper relative position, applying the usual wax plate for the type impression while the metal impression is in place, and then apply-

ing pressure to the wax plate, whereby the 45 impressed-metal-plate is picked up therewith.

2. The process of forming matrices for the production of electrotypes from combined half-tone and type forms, which consists in making an independent metal impression of 50 the half-tone, and then making a wax impression of the type, and combining the metal-impression with the wax impression in the operation of making the latter so that the parts to be reproduced are held in the 55 proper relative position.

3. The process of forming matrices for the production of electrotypes from combined half-tone and type forms, which consists in assembling the type and half-tone in proper 60 relative position, making a metal impression of the half-tone *in situ*, placing the usual wax plate over the type and impressed-metal-plate, and then subjecting said wax plate to pressure sufficient to form the type impression and pick up the impressed-metal-plate.

4. The process of forming matrices for the production of electrotypes from combined half-tone and type forms, which consists in assembling the type and half-tone in proper 70 relative position, placing a thin metal plate over the half-tone, applying pressure to said metal plate to form an impression of said half-tone, placing a wax plate for the type impression over said type and the impressed-metal-plate while the latter is in place, and then applying pressure to the wax plate whereby the type impression is formed and the impressed-metal-plate simultaneously 75 picked up.

In testimony whereof, I have signed my name to this specification, in the presence of two subscribing witnesses.

WILLIAM H. WELSH.
